United States Patent Office

Des. 180,466
Patented June 18, 1957

180,466

IDENTIFICATION BINDER CLIP

Jo Allen Bebee, Dayton, Ohio

Application October 24, 1955, Serial No. 38,526

Term of patent 3½ years

(Cl. D17—3)

Fig 1

Fig 4

Fig. 1 is a perspective view of an identification binder clip, showing my new design;

Fig. 2 is a side elevational view thereof;

Fig. 3 is an end elevational view thereof; and

Fig. 4 is a bottom plan view thereof.

I claim:

The ornamental design for an identification binder clip, as shown.
